CLAIM

The ornamental design of an inner portion of a brake rotor, as shown and described.

DESCRIPTION

FIG. 1 is a front-elevational view of an inner portion of a brake rotor;

FIG. 2 is a perspective view thereof, as viewed from a slightly sidewardly-angled, generally front-elevational view;

FIG. 3 is an enlarged, fragmented perspective view thereof; and,

FIG. 4 is another perspective view of FIG. 1, as viewed from a generally side-elevational view.
